UNITED STATES PATENT OFFICE.

HORATIO G. GILLMOR, OF WASHINGTON, DISTRICT OF COLUMBIA.

ANTICREEPER.

Application filed May 17, 1921. Serial No. 470,232.

To all whom it may concern:

Be it known that I, HORATIO G. GILLMOR, a citizen of the United States, residing at Washington, in the District of Columbia, have invented a new and useful Improvement in Anticreepers, of which the following is a specification, accompanied by drawings.

My invention relates to improvements in anticreepers or rail anchors. The object of the invention is to provide an effective device which shall be inexpensive to manufacture and may be constructed entirely from rolled material.

A further object of the invention is to provide a device in which the latitude in size of the rail bases to which the device may be applied is considerable; to provide a device which may be readily and rapidly applied to the rail with the implements in general use by track hands; and to provide a device which shall be light in weight while possessing ample strength to resist the forces which must be withstood by the device in service. Other objects and advantages of the invention will be apparent from the description hereinafter given.

In the drawings—

Figure 1, is an elevation showing the device with the rail in cross section.

Figure 2 is a side elevation showing the device in operative position upon the rail, a portion of which and of one tie are shown.

Figure 3 is a plan view looking down upon the top of the rail showing the device in operative position.

Figure 4 is an elevation with the rail in cross section showing the parts in one of the positions assumed when the device is being applied to the rail.

Figure 5 illustrates the fabrication of one of the parts from a flat rolled bar.

Like characters of reference designate like parts in the several figures of the drawing.

Referring to the drawing, A designates a rail having a base flange B resting upon and supported by cross ties of which one is designated by C.

The anticreeper consists of two co-engaging elements, a tie abutting rail base engaging element or clamp D and a dog or lock E.

The tie abutting rail base engaging clamp D may be formed from a rolled H-shaped bar having a web F and two flanges G and H. In fabricating the clamp D the two flanges are notched or slotted to form two

jaws or arms, adapted to engage the rail base at one side of the rail; and two lugs K, adapted to engage the edge of the rail base at the side of the rail opposite to that engaged by the jaws or arms I. The jaws or arms I and the lugs K are preferably formed in the flanges G and H of the clamp D by a simple operation of punching or shearing, which forms a slot in each of the two flanges G and H of the width of the rail base B and the slot is preferably given a slight downward camber or deflection as indicated in Figure 4. The web F of the clamp D is punched at L and slotted at M, 70 to receive the dog or lock E.

The dog or lock E has two arms N and O, and the arm N is provided with a lug or projection P adapted to be inserted in the opening L in the web F of the clamp D. 75 The arm O of the dog or lock E is notched at Q.

In applying the device to the rail the clamp D is placed with the jaws or arms I engaging the rail base at one side of the rail 80 and driven transversely upon the rail with either flange G or H in contact with or adjacent to a face of the tie C. While being so driven to position the lugs K will ride upon the bottom of the rail base until these 85 lugs clear the edge of the rail base at the side opposite to that engaged by the arms or jaws I. When this position is reached the resiliency of the clamp D will spring the lugs upward into engagement with the edge 90 of the rail base as illustrated in Figure 4. The dog or catch may then be placed in position by inserting the lug P of the arm N of the dog E in the aperture L of the web F of the clamp D, and then by moving the dog 95 E angularly, it may be brought into engagement with the upper corner of the rail base.

A sharp blow with a hammer or similar instrument upon the upper end of the dog E will move the arm O upon the rail base sufficiently to bring the notch Q into engagement with the upper corner of the rail base as illustrated in Figure 4, and hold the dog E in engagement with the rail base so that both hands of the person applying the de- 105

vice will be free. The dog or lock E may then be driven to the final operative position illustrated in Figure 1 by the use of a hammer or any other convenient implement. While being so driven the dog E pivots upon 110 the corner S of the aperture L in the web F of the clamp D. The surface R of the

notch Q is inclined at a relatively small angle to the surface T of the main portion of the arm O of the dog E so that the arm O will ride upon the corner of the rail base in being forced into position and will exert strong upward forces upon the clamp D drawing the clamp D up into contact with the bottom of the rail base and stressing the clamp D so that the curved or cambered portions of the slots in the flanges G and H are drawn into contact with and pressed strongly up against the bottom of the rail base as illustrated in Figure 1. As the final position of the dog E is approached the surface N of the web F of the clamp D and the surface V of the arm M of the dog E contact so that in the operative position of the parts there is sufficient area of contact of the parts to provide properly for the transmission of the stresses to which each is subject. With the parts in the operative position the sides of the aperture L and the slot M in the web F of the clamp D form abutments preventing movement of the lower portion of the dog or lock E in the direction of length of the rail and the lug P prevents lateral disengaging movement of the dog E in relation to the clamp D. In the final operative position of the parts the lugs K on the flanges G and H of the clamp D engage the edge of the rail base opposite to the arms or jaws I and prevent lateral movement of the clamp D upon the rail base. It will readily be seen that the line of the pressure of the dog or lock E against the top of the rail base, both while applying dog E and with the parts in operative position, passes through the clamp at the place of its engagement with the dog E and through the rail base at some distance in from the edge of the rail base so that with the parts in position there is no tendency for the dog or lock to become disengaged from the rail. Furthermore variations in the dimensions of the rail base do not affect the security of the engagement of the parts with each other and with the rail base, because of the resiliency of the clamp D and the dog or lock E, both of which are preferably constructed of materials permitting considerable change in form without permanent deformation. It will readily be seen that should the rail tend to move across the tie, the engagement of the flange G with the face of the tie will resist such movement. Should the initial grip of the parts upon the rail base not provide sufficient resistance to such creeping movement, slight movement of the rail in relation to the clamp D, the dog E being held at its lower end by the shoulders or abutments formed by the sides of the aperture L and slot M of the web F of the clamp D, will tilt slightly so that the grip of the anticreeper upon the rail base will be thus automatically in-

creased. The certainty of the engagement of the parts with each other and with rail is, however, not dependent in any way upon the cooperation of the parts with the tie, and should the rail move rearwardly so as to carry the clamp D away from the tie, there is no slackening of the grip of the clamp D and the dog or lock E upon the rail, even though the clamp D be held as, for example, in frozen ballast during such rearward movement, for the reason that the device would, in that event, operate to resist such rearward movement in a manner exactly similar to that in which it operates to resist the forward creeping movement. It will thus be seen that after the anticreeper has once been placed upon the rail base it is positively locked in position.

It will be noted that the device may be applied with either flange G or H adjacent the tie and that it is, therefore, reversible; and the clamp D is so constructed that the dog E cannot be positioned until the clamp D has been correctly placed with the lugs K clear of the edge of the rail base opposite the jaws I, so that the device cannot be incorrectly or improperly applied. This permits its application to be placed in the hands of the most ignorant and unskillful of track employees.

It will readily be seen that the clamp D may be easily and cheaply manufactured from a rolled bar. All that is involved in its fabrication is the cutting of the bar to length, the slotting of the two flanges to receive the rail base and the punching of the web. The dog or lock is likewise readily manufactured from a flat rolled bar. Figure 5 illustrates the simplicity of the operation involved. In Figure 5 a portion of the bar is shown after one or more of the dogs E have been made therefrom. In one operation the slot X may be punched and the bar sheared at the line W. Movement of the bar for a distance equal to the length of one dog or lock E permits the machine to punch out the slot X₁ and shear the bar at line W₁, thus forming a complete dog E. Repeating the operations for X₂, W₂, etc., the entire bar may be rapidly and inexpensively formed into dogs or locks E.

It will be understood that the embodiment of the invention herein shown is intended to illustrate the features of the invention but is not intended to limit the same to the form shown, as various embodiments of the invention may be devised which fall within the scope of the appended claims.

Having thus described my invention, what I claim as new and desire to secure by Letters Patent of the United States is:

1. A part for anticreepers comprising a slotted rolled bar with parallel end surfaces constructed to engage the top of a rail base and to so engage a rail base engaging ele-

- ment below the rail as to be angularly movable about an axis below the rail.
2. An anticreeper for railroad rails, comprising a rail gripping element constructed from a rolled bar having two rail base engaging flanges, either of which is adapted to engage a tie, formed with jaws at one end and a seat formed in the web connecting said flanges at the other end, and a rail base engaging part engaging said seat and the rail base opposite to said jaws. 5
3. A device for preventing the creeping of rails, comprising a rolled rail gripping element having a slotted flange adapted to receive a rail base and engage both the top and the bottom of the rail base at one side of the rail and the edge of the rail base at the other side of the rail, and a rail engaging device for drawing said rail gripping element into engagement with and pressing the same up against the rail bottom. 10
4. An anticreeper, comprising a rolled rail gripping element embracing the base flange at one side of a rail and provided with a portion adapted to engage the rail base at the other side of the rail and to engage a tie, said element being normally inclined downwardly from the rail bottom, and a rail engaging device engaging said element for drawing the rail edge engaging portion thereof into contact with the edge of the rail base. 15
5. A device for preventing the creeping of rails, comprising a rolled rail engaging and gripping element constructed with a plurality of tie-engaging flanges and a rail engaging part constructed to engage said gripping element for drawing said element into contact with and locking the same upon the rail base. 20
6. An anticreeper, comprising a gripping member for transverse disposition beneath a rail and provided with a plurality of rail base gripping jaws at one end and a plurality of base edge engaging portions at the other end thereof and a vertical pressure producing part arranged to engage the rail base flange above and said gripping member below the rail. 25
7. An anticreeper, comprising a gripping member arranged to be transversely disposed with relation to a rail and provided with a plurality of tie-engaging flanges each provided with a rail base gripping jaw at one end and a rail base edge engaging portion at the other end thereof and a vertical pressure producing part arranged to engage the rail base above and said gripping member below the rail. 30
8. An anticreeping device for rails, comprising an H-shaped rolled bar having flanges adapted to engage a tie and slotted to receive the rail base, and a transversely disposed vertical pressure producing part pivotally engaging said bar. 35
9. In an anticreeping device for rails, a tie engaging rail gripping element adapted to engage the rail base at one side of a rail, and a transversely movable vertically disposed part adapted to engage the rail base and said element and provided with a locking notch in the rail base engaging portion of said part. 40
10. A device for preventing the creeping of rails, comprising a transverse rolled bar notched to receive a rail base and arranged to engage a fixed portion of the roadbed and a notched rolled bar arranged to engage said bar first named and the rail base for effecting the gripping action. 45
11. A rail anchor, comprising a rolled bar adapted to engage a fixed portion of the roadbed and provided with a plurality of notched flanges arranged to receive a rail base and a second vertically disposed transversely movable notched rolled bar adapted to engage with the rail base and said bar first named to draw said bar first named into contact with and lock the same upon the rail base. 50
12. A rail anchor, comprising a transversely extending part engaging with the edges and bottom and, at one side of the rail, with the top of the rail base, a substantially vertically disposed flat bar having pivotal engagement with said part below and with the rail above the base and means for engaging a tie in opposition to the tendency of the rail to creep. 55
13. An anticreeper, comprising a rail gripping element constructed from a rolled bar and adapted to engage opposite sides of the rail base, a part so engaging the rail base and said gripping element as to be adapted to move angularly transverse to the rail about an axis below the rail for locking the anticreeper in position and means for engaging a tie in opposition to the tendency of the rail to creep. 60
14. A device for preventing the creeping of rails, comprising a rolled rail engaging and gripping element provided with means to engage the edge of a rail base at one side of the rail and adapted to embrace the top and fulcrum upon the bottom of the rail base at the other side of the rail a flat bar slotted to engage said element and the rail base to effect the gripping action and lock the device upon the rail and tie engaging means adapted to resist the tendency of the rail to creep. 65
15. An anticreeper, comprising a rolled rail engaging and gripping element adapted to engage the top and to fulcrum upon the bottom of the rail base at one side of the rail and provided with means for engaging a tie and a rail engaging device constructed to engage said gripping element at the other side of the rail to effect the gripping action. 70

H. G. GILLMOR.
